[57] CLAIM

The ornamental design for a trailer, as shown and described.

DESCRIPTION

FIG. 1 is a perspective view illustrating a trailer in accordance with my invention;

FIG. 2 is side elevation view of the trailer shown in FIG. 1 with the opposite side being substantially identical to the side shown;

FIG. 3 is a top plan view of the trailer;

FIG. 4 is a rear elevation view of the trailer; and,

FIG. 5 is a front elevation view of the trailer.

The broken lines shown in the FIGS. 1-4 drawing views are for illustrative purposes only and form no part of the claimed design.
